UNITED STATES PATENT OFFICE.

CHARLES A. ABBATH, OF QUINCY, ILLINOIS.

DESIGN FOR A BIT-BRACE RACK.

45,140.

Specification for Design.

Patented Jan. 13, 1914.

Application filed August 23, 1913. Serial No. 786,335. Term of patent 7 years.

To all whom it may concern:

Be it known that I, CHARLES A. ABBATH, a citizen of the United States, residing at Quincy, county of Adams, and State of Illinois, have invented a new, original, and ornamental Design for Bit-Brace Racks, reference being had to the accompanying drawings, forming a part thereof.

In this drawing Figure 1 is a face view of a rack embodying my invention, and Fig. 2, a side view of the same.

I claim:

The ornamental design for a bit brace rack as shown.

In testimony whereof I have signed my name to this specification in the presence of two subscribing witnesses.

CHARLES A. ABBATH.

Witnesses:

CHARLES A. WAGNER,
FRANK A. STEGEMAN.
